UNITED STATES PATENT OFFICE.

JOHN S. STITES, OF BROOKLYN, ASSIGNOR TO ELMORE, ADAMS & CO.,
OF NEW YORK, N. Y.

DESIGN FOR A BOTTLE-STOPPER.

SPECIFICATION forming part of Design No. 14,330, dated September 25, 1883.

Application filed July 19, 1883. Term of patent 14 years.

To all whom it may concern:

Be it known that I, JOHN S. STITES, a citizen of the United States, residing in Brooklyn, in the county of Kings and State of New York, have invented and produced a new and original Design for a Bottle-Stopper, of which the following is a specification.

My invention relates to the form and construction of stoppers, corks, &c., for bottles or other vessels.

It particularly relates to the shaping of stoppers in definite forms for the purpose of attracting attention to the character of the contents of the bottles.

15 The especial object of my invention is to prevent the accidental use of poisons. This I accomplish by fashioning the handle or knob of the bottle-stopper in the form of a skull or "death's-head," having projections representing the extremities of cross-bones extending outwardly from the skull. This particular design is intended to be applied exclusively to bottles or other vessels containing poisonous matter. The dangerous nature of the contents is indicated both by the peculiar and suggestive appearance of the stopper and by the feeling imparted in handling. A double safeguard is thus provided.

20 The invention is particularly serviceable in drug-stores and the laboratories of dispensing

chemists, where bottles containing poisonous matter are placed in the neighborhood of bottles holding non-poisonous substances and provided with ordinary stoppers.

The accompanying drawing shows a bottle-stopper illustrating my design.

A indicates an image or representation of a human skull or death's-head, which forms the handle or knob of the stopper, and b b indicate the projecting extremities of the cross-bones.

B is the portion of the stopper intended to close the mouth of the bottle, and is illustrated as of the usual form.

The stopper may be formed of any suitable material.

I claim as my invention—

A design for the handle or knob of a bottle-stopper, consisting of an image or representation of a skull or death's-head with the extremities of "cross-bones" projecting from the surface of said skull, as described and shown.

In testimony whereof I have hereunto subscribed my name this 18th day of July, A. D. 1883.

JOHN S. STITES.
